Bruce D. Jobse; Marlo Schepper Grolnic(57) **CLAIM**

The ornamental design for a pillow, as shown and described.

DESCRIPTION

FIG. 1 is a front, top perspective view of a pillow in accordance with the new design;

FIG. 2 is a front, left side, top perspective view of the pillow illustrated in FIG. 1;

FIG. 3 is a front elevational view of the pillow illustrated in FIG. 1;

FIG. 4 is a rear elevational view of the pillow illustrated in FIG. 1;

FIG. 5 is a right side elevational view of the pillow illustrated in FIG. 1; the left side elevational view being a mirror image thereof;

FIG. 6 is a top plan view of the pillow illustrated in FIG. 1; and,

FIG. 7 is a bottom plan view of the pillow illustrated in FIG. 1.

Any broken line illustration of environmental structure in the drawing is not part of the design sought to be patented.
